UNITED STATES PATENT OFFICE.

JAMES P. SNEDDON, OF BARBERTON, OHIO, ASSIGNOR, BY MESNE ASSIGNMENTS, TO THE STIRLING COMPANY, OF JERSEY CITY, NEW JERSEY, A CORPORATION OF NEW JERSEY.

METHOD OF FORMING HOLLOW OR TUBULAR ARTICLES.

SPECIFICATION forming part of Letters Patent No. 693,174, dated February 11, 1902.

Application filed April 12, 1901. Serial No. 55,542. (No specimens.)

To all whom it may concern:

Be it known that I, JAMES P. SNEDDON, a resident of Barberton, in the county of Summit and State of Ohio, have invented a new and useful Improvement in Methods of Forming Hollow or Tubular Articles Provided with a Diaphragm; and I do hereby declare the following to be a full, clear, and exact description thereof.

10 My invention relates to a method of forming hollow or tubular metal articles irregular in outline and provided with a diaphragm, such as serpentine boiler-headers and the like, and has for its object to provide a method for 15 forming such articles of wrought metal.

In the Niclausse and Durr boilers the water-tubes comprise an outer water-tube and an inner circulating-tube, both of which are connected to the same header, and in consequence of which the header is provided with a longitudinal diaphragm forming two compartments or passages in the header, with one of which the outer water-tubes communicate and with the other of which the inner circulating-tubes communicate, the object of this diaphragm being to separate the two currents of circulation or the "uptake" and "down-take," as they are called, in the header. These headers in Niclausse boilers must be shaped 25 to connect with a series of vertically-arranged tubes which are placed staggered, as is common in water-tube boilers, thereby necessitating a header which is sinuous or "serpentine," as it is called, in outline. Heretofore this form of header provided with a diaphragm 30 has been made only by casting. In marine and similar boilers, however, lightness in the headers is an essential requisite, and as a consequence it is desirable to make these headers 35 of wrought-iron or steel. Prior to my invention, however, it has not been possible to form serpentine headers having a diaphragm in any other manner than by casting.

It is the object of my invention to provide 40 a method for forming these headers of wrought metal or steel; and to this end it consists, generally stated, in taking a tube, heating the same, inserting therein a shaped diaphragm, and supporting said diaphragm in position in

the tube and then pressing the walls of the 50 tube down onto the edges of said diaphragm and so supporting the tube on the interior as to prevent collapse, thereby shaping the header and pressing the walls thereof firmly onto the edges of the diaphragm, whereby the 55 edges thereof are embedded in the walls to hold the diaphragm firmly in place.

The invention also consists in providing the shaped diaphragm with edge projections which embed themselves in the walls of the 60 tube when the latter are pressed down on the edges of the diaphragm, which edge projections may be made sufficiently long to penetrate the walls of the tube and be upset on the outside thereof, thereby forming a tie between the walls of the diaphragm to strengthen the same against heavy internal pressure.

In the accompanying drawings I have shown suitable apparatus for carrying out my invention, and in said drawings—

Figure 1 is a longitudinal vertical section of one form of mandrel suitable for this purpose. Fig. 2 is a longitudinal horizontal section of the same. Fig. 3 is a longitudinal vertical section of a modified form of mandrel. 75 Fig. 4 is a longitudinal horizontal section of the same. Fig. 5 is a side view, and Fig. 6 an end view, of the tube employed. Fig. 7 is a longitudinal vertical section of the dies, mandrel, and tube. Fig. 8 is a transverse section 80 of the same. Fig. 9 is a sectional detail illustrating one manner of securing the diaphragm, and Fig. 10 is a sectional detail illustrating the manner in which this is done.

I have illustrated my invention as applied 85 to the formation of serpentine boiler-headers of the Niclausse type and will describe the same as applied thereto.

The mandrel comprises a hollow box-like structure 1, the same being preferably formed 90 of cast metal, said mandrel being provided with the flat side walls 2 2 and with the corrugated top and bottom walls 3 3, the corrugations 4 on said walls extending at an angle or obliquely across the bottom and top faces in order to 95 adapt the header to the inclined position of the water-tubes of the boiler. In case, however, the header is to be used with a boiler

having horizontal tubes, these corrugations 4 will extend straight across the top and bottom faces of the mandrel. The side walls of the mandrel are provided with the openings 5 in order to lighten the same, and in order to strengthen the hollow mandrel-body the same may be provided with transverse webs 6, as shown in Figs. 1 and 2, or transverse struts 7, as shown in Figs. 3 and 4. These internal supports, whether webs or struts, extend in a substantially vertical line between the top and bottom faces of the mandrel in order to receive the direct thrust of the forging-dies, as will hereinafter appear. The webs 6 (shown 15 in Figs. 1 and 2) are shown as extending diagonally across the mandrel-body between the side walls to correspond to the oblique or diagonal arrangement of the corrugations 4, as above explained.

20 The mandrel-body is formed in two or more longitudinal sections 8, the number of said sections depending on the number of diaphragms to be secured in the article, said body being divided on a vertical plane. The meeting faces of these sections are shown stepped or jogged, as at 9, in order to conform to the shape of the diaphragm 10, the latter having a stepped or jogged shape in order to provide faces 11, which are at right angles to the inclined water-tubes of the boiler, said faces being provided with the openings 12, through which pass the circulating-tubes of the boiler, as will be readily understood by those skilled in the art.

25 The dies for shaping the header or other article are shown in Figs. 7 and 8, and the same comprise a stationary bottom die 13 and a movable top die 14, both of which are corrugated transversely to correspond to the corrugations of the mandrel, said corrugations, if necessary, being also inclined or oblique, as shown. If, however, the header is to be adapted for boilers having horizontal water-tubes, these corrugations will run straight across the 30 dies, the same as the corrugations 4 on the mandrel and the webs 6 therein. 15 represents a stationary side die, the same being preferably formed integral with the bottom die 13; but this is not necessary. Said side die is provided with a flat face, as shown, and 16 represents a movable side die formed with a similar flat face. The die 14 is moved, preferably, by means of a hydraulic cylinder (not shown) or equivalent means, and the die 16 is likewise preferably moved by a hydraulic cylinder, although it may be moved by a wedge or any other means. The tube 17 used for the formation of these headers is rectangular in cross-section, as shown in Figs. 5 and 6. The 35 diaphragm is brought to the desired shape in any suitable way, and when the header is to be serpentine in form the diaphragm is made with serpentine edges to conform substantially to the shape of the finished header.

40 This diaphragm is made about one thirty-second of an inch wider than the height of the mandrel and is placed between the sec-

tions 8 thereof and then, together with these sections, is slipped into the squared tube 17, which has first been raised to a suitable forging heat and placed, together with the same, upon the bottom die 13, as shown in Figs. 7 and 8. The side die 16 is then moved up against the tube 17 and inclosed mandrel, and the die 14 is then brought down to compress the walls of the tube against the mandrel, thereby shaping the header and at the same time pressing the top and bottom walls of the tube against the edges of the diaphragm 10, so that the latter will become embedded in said top and bottom walls, as shown in Fig. 8, thereby forming a secure fastening for said diaphragm in the header.

In the shaping of the header the metal in the side walls between the points 18 and 19 must be upset into the metal between the points 19 and 20, or, in other words, the height of the side walls of the tube must be reduced an amount equal to the distance between the points 18 and 19. In order to properly upset the metal to this amount and leave the walls of uniform thickness, it is desirable that the side die 16 be at first brought against the side of the tube but lightly and then after the die 14 has been brought down the said side die will be pressed firmly against the side of the tube, thereby smoothing out and properly shaping the upset metal in the side walls of the tube. In carrying out the invention it may even be found desirable to give the dies 14 and 16 alternate slight inward and outward movements in order to effect a better upsetting and shaping of this metal, and it is for this reason that the side die 16 should be moved by means of a hydraulic cylinder or other means which will permit its ready inward and outward movement.

After the forging or shaping of the header is completed the side die 16 is moved back and the top die 14 raised, and the said header is then removed from the dies and another put in its place and the operation repeated. The mandrel-sections 8 are then broken out by means of a bar or similar device, and the broken pieces are again taken to the melting-pot and used in the casting of other mandrels. The said mandrel offers a rigid support to the thrust of the forging or shaping dies, and therefore it is practically impossible for the header to collapse at one or more points. The 45 mandrel-sections, furthermore, are readily removable, and inasmuch as the metal can again be used the cost of said mandrel-sections is practically only the cost of forming and pouring the molds therefor.

In some cases it may be desirable to provide additional securing means for the diaphragm, and as such means the said diaphragm may be formed with the edge projections or teats 21, (shown in Fig. 7,) which projections are located in the concave edge portions of the diaphragm, so as not to require an additional-sized tube 17, which edge portions 21 are caused to embed themselves in

the top and bottom walls of the header, thereby holding the diaphragm very securely in place. These edge projections may be made long enough, as shown at 22, Fig. 10, to penetrate the walls of the header and to be upset on the outside thereof, as shown at 23, Fig. 9, so that the said projections 22, together with the diaphragm 10, form a tie between the top and bottom walls of the header and strengthen the same against heavy internal pressure, as will be readily understood.

While I have shown my invention applied to the formation of serpentine wrought-metal headers provided with a diaphragm, I wish it understood that it is not limited thereto, but may be used in the formation of wrought-metal headers of other than serpentine form or any other tubular wrought-metal articles provided with a diaphragm whether such articles be rectangular in cross-section or be serpentine in longitudinal section or not. In these modifications of my invention it will only be necessary to change the shape of the mandrel-sections and of the dies to correspond to the shape of the article desired to be formed. I also wish it understood that my invention is not limited to the use of the particular sectional mandrel shown nor to one having only two longitudinal sections, it being sufficient for my invention that the diaphragm is supported in position to have the walls of the tube pressed thereagainst and that the said tube be given such internal support as will prevent its collapse during the forging process.

The apparatus herein shown and described is not claimed herein, but is claimed in an application of even date herewith, Serial No. 55,543.

What I claim, and desire to secure by Letters Patent, is—

1. The method of forming wrought-metal tubular articles provided with a longitudinal diaphragm, which consists in supporting a shaped diaphragm longitudinally within the tube and then pressing the walls of the latter against the edges of the diaphragm to cause the latter to firmly engage said walls.

2. The method of forming wrought-metal tubular articles of irregular outline longitudinally provided with a longitudinal diaphragm, which consists in supporting the shaped diaphragm longitudinally within the tube and then pressing the walls of the latter against the edges of the diaphragm to cause the latter to embed themselves in said walls.

3. The method of forming wrought-metal tubular articles of irregular outline longitudinally provided with a longitudinal diaphragm, which consists in heating a section of tube, inserting therein a shaped diaphragm and supporting the same longitudinally in the tube, and then pressing the walls of the latter against the edges of the diaphragm to cause the latter to embed themselves in said walls.

4. The method of forming wrought-metal tubular articles provided with a diaphragm,

which consists in taking a shaped diaphragm provided with edge projections, supporting the same within the tube, and then pressing the walls of the latter against the edges of the diaphragm to cause the projections on the latter to embed themselves in said walls.

5. The method of forming wrought-metal tubular articles provided with a diaphragm, which consists in taking a shaped diaphragm with edge projections, supporting the same within the tube, and then pressing the walls of the latter against the edges of the diaphragm to cause said projections to penetrate said walls and be upset on the outside thereof.

6. The method of forming wrought-metal tubular articles provided with a diaphragm, which consists in supporting a shaped diaphragm within the tube and supporting the tube on the interior, and then pressing the walls of the tube while so internally supported against the edges of the diaphragm whereby the said article is shaped and the edges of the diaphragm caused to embed themselves in the walls thereof.

7. The method of forming wrought-metal tubular articles provided with a diaphragm, which consists in taking a squared tube, heating the same, inserting a shaped diaphragm therein, and supporting said tube on the interior, and then while so interiorly supported pressing the walls thereof against the edges of the diaphragm whereby the article is shaped and the diaphragm firmly secured therein.

8. The method of forming wrought-metal tubular articles provided with a diaphragm, which consists in taking a diaphragm having sinuous edges provided with projections on their concave portions, supporting the same within the tube, and then pressing the walls of the latter against the edges of the diaphragm to cause the edge projections thereof to embed themselves in said walls.

9. The method of forming wrought-metal tubular articles provided with a diaphragm, which consists in taking a diaphragm having sinuous edges provided with projections on their concave portions, supporting the same within the tube, and then pressing the walls of the latter against the edges of the diaphragm to cause said projections to penetrate said walls and be upset on the outside thereof.

10. The method of forming wrought-metal tubular articles provided with a diaphragm, which consists in taking a diaphragm with steps or jogs, supporting the same within the tube, and then pressing the walls of the latter against the edges of the diaphragm to cause the latter to embed themselves in said walls.

In testimony whereof I, the said JAMES P. SNEDDON, have hereunto set my hand.

JAS. P. SNEDDON.
